FIG. 17

FIG. 18

FIG. 19

FIG. 21

FIG. 22

FIG. 1 is a front perspective view of a desk telephone stand showing our new design;

FIG. 2 is a side elevation thereof, the opposite side being a mirror image of the side shown;

FIG. 3 is a front elevation thereof;

FIG. 4 is a top plan view thereof; and

FIG. 5 is a rear elevation thereof;

FIG. 6 is a front perspective view of a second modified embodiment of the stand shown in FIG. 1 in the form of a wall telephone stand;

FIG. 7 is a side elevation thereof, the opposite side being a mirror image of the side shown;

FIG. 8 is a top plan view thereof;

FIG. 9 is a front elevation thereof; and

FIG. 10 is a bottom plan view thereof;

FIG. 11 is a top plan view of a third modified embodiment of the forms disclosed in FIGS. 4 and 9; and

FIG. 12 is a top plan view of a fourth modified embodiment of the forms disclosed in FIGS. 4, 9, and 11.

This is a continuation-in-part of copending design application Ser. No. 424,413, filed Dec. 13, 1973 which was a continuation-in-part of design application Ser. No. 364,704, filed May 29, 1973 and now both abandoned.

We claim:

The ornamental design for a telephone stand, substantially as shown and described.
